UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR A LAMP BASE OR SIMILAR ARTICLE.

Application filed September 15, 1927. Serial No. 23,418. Term of patent 3½ years.

To all whom it may concern:

Be it known that I, JOHN A. BOEHRINGER, one half only being shown in detail, the a citizen of the United States, residing at 145-58 Aberdeen Street, Springfield, Long Island, in the county of Queens and State of New York, have invented a new, original, and ornamental Design for a Lamp Base or Similar Article, of which the following is a specification, reference being had to the accompanying drawing, forming part thereof.

Figure 1 is a plan view of a lamp base one half only being shown in detail, the other half being an exact duplicate, showing my new design.

I claim:

The ornamental design for a lamp base or similar article, as shown.

JOHN A. BOEHRINGER.
